(57) **CLAIM**

The ornamental design for a wheel hub cap assembly, as shown and described.

DESCRIPTION

FIG. 1 is a perspective view of a main body of the wheel hub cap assembly showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof;

FIG. 8 is a bottom plan view of thereof;

FIG. 9 is a perspective view of an elastic buckle of the wheel hub cap assembly;

FIG. 10 is a perspective view of FIG. 9 from another angle;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a top plan view of FIG. 9;

FIG. 16 is a bottom plan view of FIG. 9;

FIG. 17 is a perspective view of the wheel hub cap assembly; and,

FIG. 18 is an exploded view of the wheel hub cap assembly.
